CLAIM

The ornamental design for a sling bag as shown and described.

DESCRIPTION

FIG. 1 is a front, left and top perspective view of a sling bag showing my new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is a rear, left and bottom perspective view thereof;

FIG. 9 is an enlarged view of a portion labeled as "9" on FIG. 6; and,

FIG. 10 is an enlarged view of a portion labeled as "10" on FIG. 6.

The long dash-short dash broken lines depict enlargement boundaries that form no part of the claim.

1 Claim, 10 Drawing Sheets
